COMBINATION WRENCH AND PLIERS

Ernest Cullen, San Diego, Calif., assignor to
John B. Smiley, Los Angeles, Calif.

Application December 22, 1932, Serial No. 648,459

10 Claims. (Cl. 7—3)

My present invention relates to a combination tool, and particularly to a combination wrench and pliers, or a combination pliers and chain tongs; certain features, however, being applicable to various types of chain tongs.

The objects of this invention are:

First, to provide a combination tool of this class whereby most of the usual sizes of objects, gripped by pliers, may be gripped by the tool, and whereby also relatively large pipes or other objects may be tightly gripped for rotating or holding the same;

Second, to provide a tool of this class whereby a small pair of pliers equipped with the flexible element of my invention may be effectively used on large diameter objects which cannot be gripped and held by a pair of pliers without the flexible element, thus adapting the tool for gripping and holding objects over a wide range of diameters or dimensions;

Third, to provide a tool of this class whereby the jaw and handle members of the pliers may be securely fastened together and, when so fastened together, may serve as a very light but strong lever of a chain tong for gripping relatively large pipes or other objects;

Fourth, to provide chain tongs or a combination tool of this class in which the free end of the chain or other flexible member is threaded 30 through a clevis and in which the former is provided with longitudinally spaced depressions into which the free end of the clevis is adapted to enter and tightly secure the chain or other flexible member when the latter is under tension, thus providing means whereby the tool may be easily and quickly adjusted to various sizes, and readily held to such adjustment, and also providing means whereby the chain or other flexible member may be tightly gripped without undue strain on the securing means;

Fifth, to provide, in chain tongs or a combination tool of this class, a flexible gripping member which may be easily and quickly attached to or removed from a lever or a pair of pliers so that the flexible member may be readily replaced or so that the pliers may be used as pliers without unnecessary appendages;

Sixth, to provide a tool of this class whereby the chain or other flexible member may be made 50 to assist in holding objects gripped between the jaw members of the pliers; and,

Seventh, to provide a tool of this class which is very simple and economical of construction, durable, efficient, and which will not readily deteriorate or get out of order.

With these and other objects in view, as will appear hereinafter, I have devised a combination tool having certain novel features of construction, combination and arrangement of parts and portions, as will be hereinafter described in detail and particularly set forth in the appended claims, reference being had to the accompanying drawing and to the characters of reference thereon which form a part of this application, in which:

Figure 1 is a side view of my combination tool in its preferred form of construction, showing the same in position to rotate a pipe, and showing by dotted lines such pipe and a portion of the flexible member in a position for rotating the pipe in the opposite direction; Fig. 2 is an edge view thereof; and, Fig. 3 is a fragmentary sectional view thereof taken through 3—3 of Fig. 1.

Like characters of reference refer to similar parts and portions throughout the views of the drawing.

The pliers employed in carrying out my invention is similar to pliers now in use except as hereinafter set forth. These pliers consist of a pair of jaw and handle members 1 and 2 pivotally connected intermediate their ends by a bolt or pivot member 3. This bolt or pivot member is secured to one of the jaw and handle members and is flattened at its shank and extends through connected circular holes in the other jaw and handle member, as shown in the drawing, so that the jaws of the pliers may be readily extended or contracted for gripping large or small objects as in pliers now in use. The jaws of the jaw and handle members are provided with teeth 1a and 2a at their adjacent sides for rigidly holding objects gripped therebetween.

The jaw and handle members 1 and 2 are provided at the ends of their handle members with a link 4 which is pivotally connected to the member 2 by a pin 5 and is adapted to extend around the member 1, and preferably to enter a slight depression in the latter member. It will be noted that the link or locking member 4 serves the particular purpose of holding or securing the members 1 and 2 together as a rigid lever so that the device may be effectively used as a pipe tong. The link 4 is not used for holding the jaw portions of the members 1 and 2 together to facilitate the retention of an object between the jaws of the pliers, as heretofore used.

The jaw and handle member 1 is provided at the outer side of its jaw portion, and backwardly from the teeth, as will be described hereafter, with a lug 1b which is in the form of an eye, being

provided with a transverse hole 1c. The flexible member 6 of my tool, which flexible member in this instance is a chain, is threaded through the hole in the lug or eye member, and is prevented from being pulled through the eye member by an anchor or retaining member 7. This member 7 is pivotally connected to the chain and is provided at the inner end of its shank with an enlarged transverse portion 7a which engages and is retained by the inner side of the lug or eye member. This lug or eye member is provided at its inner side with a rounded pivot portion 1d against which the enlarged transverse portion 7a rests so that all strain is applied to the member 7 in tension.

The chain 6 extends around the jaw portion of the tool and is threaded with its other or free end through an eye member 8 which is in the form of a clevis pivotally connected, by means of a pin 9, to the other jaw and handle member 2. This clevis 8 clamps the chain against the cheek of the jaw and handle member 2 when outward force is applied on the chain.

At the latter end of the chain is provided an end member 10 which is pointed at its end and facilitates the threading of the chain through the eye members 1b and 8.

At the outer sides or outer portions of the cheeks of the jaw and handle members 1 and 2 are provided transverse teeth 1e and 2b, respectively, as in usual wrench construction, to facilitate the gripping of the pipe 11.

It will be here noted that if the pipe or other object 11 engages the teeth 1e, as shown by solid lines in Fig. 1, the pipe or other object may be rotated in one direction. Then if the chain or other flexible member 6 is loosened and the pipe or other object placed in engagement with the teeth 2b, and the chain or flexible member again tightened, the pipe or other object may be rotated in the opposite direction without removing the same from the tool or changing the tool about.

It will be also noted that the chain or other flexible member may be readily and entirely removed from the jaw or handle members, by withdrawing the flexible member from the eye 1b by means of the retaining member 7, thereby permitting the tool to be used as a pair of pliers only.

It will be also noted that an object may be held between the jaws of the tool and held in place by the chain or other flexible member.

Though I have shown and described a particular construction combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent, is:

1. A combination tool comprising a pair of pliers consisting of pivotally connected jaw members, each having teeth at the outer side of its jaw portions, and a flexible member extending around said teeth and attachable at its opposite end portions to the opposite sides of the pliers and outer sides of said jaw portions for coacting with the teeth for gripping a pipe.

2. A combination tool comprising a pair of pliers consisting of pivotally connected jaw members, each having teeth at the outer side of its jaw portions, one of the jaw members having an eye member and the other having a securing clevis

at said outer sides beyond the teeth, and a flexible member extending through said eye member and having an enlarged portion adapted to retain said flexible member in said eye member, said clevis adapted adjustably to engage the other end portion of said flexible member.

3. A combination tool comprising a pair of jaw members pivotally secured together intermediate their ends, forming a pair of pliers, said jaw members having jaw portions at one end, means for detachably locking said jaw members together as a rigid unit, and a flexible member extending around said jaw portions, said flexible member being attachable at its opposite end portions to the outer sides of the jaw portions of said jaw members.

4. A combination tool comprising a pair of jaw members pivotally secured together intermediate their ends, forming a pair of pliers, said jaw members having jaw portions at one end, means for detachably locking said jaw members together as a rigid unit, one of the jaw members having an eye member and the other having a securing clevis at the outer side, and a flexible member extending around said jaw portions, said flexible member extending through said eye member and having an enlarged portion adapted to retain said flexible member in said eye member, said clevis adapted adjustably to engage the other end portion of said flexible member.

5. A combination tool comprising a pair of jaw members pivotally secured together intermediate their ends, forming a pair of pliers, said members having jaw portions at one end, a link secured to the handle end of one jaw member and adapted to extend over the handle end of the other jaw member for detachably locking said jaw members together as a rigid unit, one of the jaw members having an eye member and the other having a securing clevis at the outer side, and a flexible member extending around said jaw portions, said flexible member extending through said eye member and having an enlarged portion adapted to retain said flexible member in said eye member, said clevis adapted adjustably to engage the other end portion of said flexible member.

6. A combination tool, comprising a pair of pliers consisting of pivotally connected jaw members forming together a jaw portion at one end of the pliers, the pliers having teeth at the outer side of its jaw portion and securing means on each jaw member at the opposite sides of the jaw portion, and a flexible member securable at one end to one of said means and adjustably securable near its opposite end to the other of said means.

7. In a tool of the class described, a lever having an eye at one side, a securing eye member pivotally mounted at the opposite side, and a flexible member having an enlarged portion at one end, said flexible member being threaded, with the end opposite the enlarged portion, through the first eye and adapted to be retained therein at and by said enlarged portion, and adapted to be wholly withdrawn therefrom, the opposite end of said flexible member being adapted also to be threaded through the pivotally mounted eye member and clamped against the lever thereby.

8. In a combination tool, a pair of jaw members pivotally secured together forming a pair of pliers, said jaw members having jaw portions adjacent one end, one of the jaw members having an eye at the outer side, a securing eye

member pivotally mounted at the outer side of the other jaw member, and a flexible member having an enlarged portion at one end, said flexible member being threaded, with the end opposite the enlarged portion, through the first eye and adapted to be retained therein at and by said enlarged portion, and adapted to be wholly withdrawn therefrom, the opposite end of said flexible member being adapted also to be threaded through the pivotally mounted eye member and clamped thereby against the adjacent jaw member.

9. In a tool of the class described, a lever, a sprocket chain attached at one end to one side of said lever and extending around one end thereof, said chain having longitudinally spaced depressions, and a clevis pivotally mounted on said lever and extending around the opposite side of the lever, said clevis adapted to receive the opposite end of the chain and the outer wall of said clevis being adapted to enter said depre-

sions, said chain being clamped tightly against said lever by said clevis when said clevis is directed outwardly and inclined toward said end of the lever and when the chain is under tension, for adjustably securing said opposite end of the chain. 5

10. A combination tool comprising a plier means having a jaw portion at one end, and a flexible means extending around the exterior of said jaw portion, one of said means having gripping elements at the side adjacent the other of said means, said plier means consisting of pivotally connected jaw members, each jaw member having securing means on the outer side thereof and at the opposite sides of the jaw portion, said 15 flexible means being securable at one end to one of said securing means and adjustably securable at its opposite end portion to the other of said securing means. 10

ERNEST CULLEN. 20
